UNITED STATES PATENT OFFICE.

HENRY F. SCHMIDT, OF PITTSBURGH, PENNSYLVANIA, ASSIGNOR TO WESTINGHOUSE ELECTRIC & MANUFACTURING COMPANY, A CORPORATION OF PENNSYLVANIA.

MARINE TURBINE.

1,345,641.

Specification of Letters Patent. Patented July 6, 1920.

Application filed September 27, 1916. Serial No. 122,506.

To all whom it may concern:

Be it known that I, HENRY F. SCHMIDT, a citizen of the United States, and a resident of Pittsburgh, in the county of Allegheny and State of Pennsylvania, have made a new and useful invention in Marine Turbines, of which the following is a specification.

This invention relates to turbines and particularly to turbine installations adapted for use in marine propulsion.

The object of this invention is to produce an organized turbine unit, in which means are employed for obtaining high economy throughout a wide range of loads and speeds.

A further object is to produce a marine turbine unit so subdivided that the unit is capable of developing substantially full speed under emergency conditions or when one or another of the sections are rendered inoperative.

A further object is to produce a marine turbine unit in which means are employed for reversing the vessel at different speeds and at the same time maintaining a high economy in the operation of the turbine. A further object is to produce a turbine unit which is lighter than other units now in use and known to me having the same capacity and one in which the friction losses are reduced under light load and low speed conditions.

These and other objects which will be made apparent throughout the further description of my invention are attained by means of apparatus embodying the features herein described and illustrated.

In the drawing accompanying and forming a part hereof, Figure 1 is a diagrammatic plan view of a turbine installation embodying my invention. Fig. 2 is a diagrammatic sectional view of a low pressure section, which may be substituted for one of the low pressure sections of the apparatus shown in Fig. 1.

The apparatus illustrated, includes a high pressure turbine section 3 and two low pressure sections 4 and 5. The separate sections are shown geared to a single driven agent, as for example the propeller shaft 6, by means of a reduction gearing 7.

The high pressure section illustrated, includes an ahead element and an astern element, both of which are located within the same casing and are provided with a common rotor, which is illustrated as operatively coupled or connected to a pinion 8, which forms an element of a reduction gearing 7, and meshes with the large or main gear 9. The ahead element of the high pressure section includes two stages 10 and 11. Both stages are shown as of the impulse type and as comprising one or more expansion nozzles and two rows of impulse blades which are mounted upon the same blade carrying wheel. It will be understood that an intermediate row of stationary directing vanes is employed between each row of moving blades of each stage. The stage 10 is essentially a high pressure stage and includes expansion nozzles 12 which receive high pressure fluid and deliver it to the first row of moving blades forming a part of the stage. Means may be employed for shutting off one or more of the nozzles so that the amount of fluid delivered to the unit may be proportioned, to the load, without throttling the fluid. The stage 11 may be termed an intermediate pressure stage, and communicates with the stage 10 by means of one or more stage nozzles 14, which, if desired, may be provided with means for closing off one or more of the nozzles in accordance with variations in the amount of motive fluid, (hereinafter termed steam), delivered to the stage 10.

The reversing element, illustrated as forming a part of the high pressure section 3, comprises a single impulse stage, which is similar to the stage 10, except that it is capable of driving the turbine in the opposite direction. It includes one or more delivery nozzles 15 which may be capable of being separately controlled.

Under full load conditions, or while the marine turbine is driving the vessel ahead and at maximum speed, a portion of the steam issuing from the last row of blades of the ahead stage 10 is delivered to the low pressure section 4, whereas the remainder of the steam is delivered to the intermediate stage 11. The steam issuing from the last row of blades of the intermediate stage 11

is delivered to the ahead element of the low pressure section 5, from which it is discharged into the exhaust.

As illustrated the ahead element of the low pressure section 4 is of the full peripheral admission type, that is steam is simultaneously delivered to all of the blades of a single row, whereas the separate ahead stages of the high pressure section are what 10 may be termed partially or variable admission types of turbine elements, since the steam may be delivered to a portion only of the blades of a single row. The ahead element of the section 4 is also shown as of the 15 type in which a single row of moving blades is included in each stage. In this connection attention may be called to the fact that the word "stage" is employed herein to designate coöperating turbine elements which 20 expand the steam and abstract all of the kinetic or velocity energy rendered available by the expansion. After the steam has traversed the working passages of the ahead element of the section 4, it is discharged 25 through an exhaust port 16 which may communicate with a condenser, not shown.

The low pressure section 5 is illustrated as including two low pressure ahead stages 17, through which the steam flows in opposite 30 axial directions. These stages operate in parallel on steam discharged from the intermediate stage 11 and are both of the full peripheral admission type with one or more moving rows of blades per stage. As shown, 35 each stage includes a series of expanding nozzles 18 and two rows of moving blades which are mounted on a blade carrying wheel, and are arranged to abstract all of the velocity energy occasioned by expanding 40 the steam as it traverses the expanding nozzles of the stage. Each stage 17 communicates with a separate exhaust port 19, which may in turn communicate with a condenser.

When the turbine is propelling the vessel 45 ahead, and at maximum speed, steam is delivered to the high pressure stage 10 through all of its nozzles 12. The steam issuing from the last row of blades of this stage is divided into two streams one of which is 50 delivered through piping 20 to the inlet port 21 of the ahead element of the low pressure section 4, whereas the other stream is delivered through the stage nozzles 14 to the intermediate stage 11. The steam issuing 55 from the last row of blades of this stage is delivered through piping 22 to the inlet port 23 of the ahead stages of the low pressure section 5. It will be noted that the ahead element of the section 4 is provided with two 60 inlet ports 21 and 21^a. The port 21 is so located that fluid delivered through it bypasses the first stages of the element, whereas the port 21^a is so located that the fluid delivered through it passes in series through 65 all of the ahead stages of the section 4. The

piping 20 is provided with a valve 21^b, which may be employed to cut off the delivery of fluid through the port 21 when the section 4 is receiving steam through the port 21^a and a valve 21^c is provided to cut off the delivery of fluid through the port 21^a. 70

When the turbine is operating at reduced speed or is driving the vessel ahead and at a speed which, in naval parlance may be termed cruising speed, a valve 24, located in 75 the piping 20 is closed, and consequently all of the steam issuing from the last row of blades of the high pressure stage 10 is delivered to the intermediate stage 11. All the fluid issuing from the last row of blades of this stage is delivered through piping 25 and the piping 20 to the inlet port 21^a of the low pressure section 4. The piping 25 is provided with a valve 26 which is closed under full power conditions or when the valve 24 80 is open. The valve 21^b is open and the valve 21^c is closed under full power conditions, whereas the valve 21^c is open and valve 21^b closed under reduced power conditions. The piping 22 is also provided with a valve 27 85 which is closed while the turbine unit is developing reduced speed. 90

It will be apparent that the arrangement of turbine sections illustrated lends itself to various combinations which may be employed for developing power at different speeds, for example; the valve 27 may be open when both the valves 24 and 26 are closed, or the valve 27 may be open when the valve 24 is closed and the valve 26 is open. With this arrangement of valves the fluid issuing from the last row of blades of the intermediate section will be divided into two streams, one of which is delivered to 95 section 4, and the other to the section 5. 100

The reversing element of the low pressure section 4 is illustrated as a single stage of the two velocity drop impulse type and its delivery nozzles 28, receive steam discharged from the reversing element of the high pressure section 3 through piping 29. The section 5, as shown is provided with two reversing elements 30 which are located on opposite sides of the ahead elements 17 and through which steam flows in opposite axial 110 directions. Each of these reversing elements is illustrated as a single impulse stage and is similar to the stage which forms the reversing element of the section 4. Both the reversing stages of the section 5 receive 115 steam discharged from the reversing stage of the high pressure section 3. 120

When the turbine is reversing at full speed, steam is delivered to all of the nozzles 15 of the reversing stage forming a 125 part of the high pressure section 3. The steam issuing from the last row of blades of this stage is divided into three streams, one of which is delivered through the piping 29, piping 31, and a branch piping 32 to one 130

reversing stage of the element section 5; one stream is delivered through the branch pipe 33 to the other reversing stage 30 of the section 5, and the third stream is delivered to the reversing element of the section 4 through the piping 29. The reversing stage of the low pressure section 4 discharges through the exhaust port 16 of that section and each reversing stage of the low pressure section 5 discharges through one of the exhaust ports 19 of that section. When the turbine is reversing at reduced speed a valve 34 in the pipe 31 is closed and consequently the steam supply to the reversing stages of the section 5 is cut off and steam is then delivered to the reversing stage of the high pressure section 3 and to the reversing stage of the low pressure section 4. The piping 29 is provided with a valve 35 which may be closed to shut off communication between the reversing stage of the high pressure section 3 and reversing stage section 4. When this valve is closed the valve 34 must be opened and all of the steam discharged from the reversing stage of the high pressure section will then be divided in two streams and delivered to the reversing stages of the low pressure section 5. With this arrangement the turbine may be reversed at full speed, with all of the reversing stages receiving steam; it may be reversed at intermediate speed with the reversing stages of sections 3 and 5 receiving steam; or it may be reversed at low speed with the reversing stages of the sections 3 and 4 receiving steam.

As illustrated the section 4 is operatively connected to pinion 36, which is similar to the pinion 8, and, meshing with the large gear 9, forms a part of the reduction gearing 7. This pinion may, and preferably will be of larger diameter than the pinion 8. The low pressure section 5 is shown operatively connected to the pinion 37, which meshes with the gear 9 and forms a part of the reduction gearing 7 and which may be of different diameter from either gears 8 or 36. It will be apparent that a disconectible clutch or coupling 39 may be located between each pinion and the turbine section driving it.

In the drawings I have shown a valve 40 located in the pipe 20 so arranged that it is capable of cutting off communication between the high pressure section 3 and the low pressure section 4. I have also shown the pipe 20 provided with a high pressure steam connection 41 which is so located, with relation to the valve 40, that it is capable of delivering high pressure steam to the inlet port 21 of the section 4 when the valve 40 is closed. I have also shown a high pressure steam supply 42 communicating with the pipe 22 and so located that it is capable of delivering high pressure steam to the port 23

of the section 5, when the valve 27 is closed. With this arrangement high pressure steam may be delivered to either or both of the low pressure sections under emergency conditions.

I have also shown a high pressure steam connection 43 on the piping 29 so arranged that high pressure steam may be delivered to the reversing stage of the section 4 when the valve 35 is closed. A high pressure steam connection 44, communicates with the branch piping 33 so that high pressure steam may be delivered to both the reversing stages 30 of the low pressure section 5 when the valve 34 is closed.

While I have illustrated what I now consider to be the preferred embodiment of my invention, it will be apparent to those skilled in the art that various changes, modifications, substitutions, additions and omissions may be made in the apparatus illustrated without departing from the spirit and scope of the invention as set forth in the appended claims.

What I claim is:

1. A turbine unit comprising a high pressure section adapted to pass all fluid required under full power conditions and two low pressure sections, a separate shaft driven by each section, and means for delivering motive fluid from one stage of the high pressure section to one low pressure section, and from another stage of the high pressure section to the other low pressure section under full power conditions.

2. A turbine unit comprising a multi-stage high pressure section adapted to pass all fluid required under full power conditions and two low pressure sections, means for delivering motive fluid from one stage of the high pressure section to one low pressure section and from a stage of lower pressure of the high pressure section to the other low pressure section under full power conditions, and means for delivering fluid to both low pressure sections from the stage of lower pressure of the high pressure section under reduced power conditions.

3. A turbine unit comprising a high pressure section adapted to pass all fluid required under full power conditions and at least one low pressure section, means for delivering motive fluid from one stage of the high pressure section to the low pressure section under full power conditions and for delivering motive fluid from a stage of lower pressure of the high pressure section to the low pressure sections under reduced power conditions.

4. A turbine unit comprising a high pressure section adapted to pass all fluid required under full power conditions, and at least two low pressure sections, means for delivering motive fluid from different stages of the high pressure section to the low pres-

sure sections during full power conditions and means for delivering motive fluid from a stage of the high pressure section to one low pressure section only during reduced power conditions.

5. A turbine unit comprising a high pressure section, adapted to pass all fluid required under full power conditions, at least two low pressure sections, means for delivering motive fluid from one stage of the high pressure section to one low pressure section, means for delivering motive fluid from another stage of the high pressure section to another of the low pressure sections during full power conditions, and means for cutting off the supply of fluid to one low pressure section under reduced power conditions.

6. A turbine unit comprising a high pressure section adapted to pass all fluid required under full power conditions, at least two low pressure sections, means for delivering motive fluid from one stage of the high pressure section to one low pressure section, means for delivering motive fluid from another stage of the high pressure section to another of the low pressure sections during full power conditions, and means for cutting off the normal supply of fluid to one low pressure section and for delivering fluid thereto from a stage of lower pressure when the unit is developing reduced power.

7. A turbine unit comprising a high pressure section adapted to pass all fluid required under full power conditions, a low pressure section, means for delivering fluid from one stage of the high pressure section to the low pressure section under full power conditions, means for delivering motive fluid from a stage of lower pressure of the high pressure section to the low pressure section during reduced power conditions, a second low pressure section, and means for delivering motive fluid from one of the stages of the high pressure section to said second low pressure section.

8. A turbine unit comprising a high pressure section adapted to pass all fluid required under full power conditions and two low pressure sections operating in parallel on fluid discharged from the high pressure section under full power conditions, each low pressure section receiving fluid discharged from a separate stage of the high pressure section.

9. A turbine unit comprising a multi-stage high pressure section adapted to pass all fluid required under full power conditions, two low pressure sections adapted to operate in parallel on fluid delivered from the high pressure section under full power conditions, means for cutting off the supply of fluid to one low pressure section, and for delivering fluid to the other section from a stage of lower pressure under reduced power conditions.

ditions than that from which it receives fluid under full power condition.

10. A turbine unit comprising a multi-stage high pressure section, a single flow low pressure section, a double flow low pressure section, means for operating said low pressure sections in parallel on fluid discharged from the high pressure section under full power conditions, and means for cutting off the supply of fluid to the double flow section and for delivering fluid to the single flow section from a stage of lower pressure, during reduced power conditions.

11. A turbine unit comprising a multi-stage high pressure section, a double flow low pressure section receiving fluid from one stage of the high pressure section, a single flow low pressure section and means for cutting off the delivery of fluid to the double flow section under reduced power conditions and for placing the single flow section in communication with the stage supplying fluid to the double pressure section.

12. A turbine unit comprising a high pressure section, a separate double flow low pressure section, a separate single flow low pressure section, means for delivering fluid from the high pressure section to the double flow section and means for substituting the single flow section for the double flow section under reduced power conditions.

13. A turbine unit comprising a multi-stage high pressure section, a separate double flow low pressure section, a separate single flow low pressure section, means for delivering fluid from one stage of the high pressure section to the single flow section, means for delivering fluid from a stage of lower pressure of the high pressure section to the double flow section, and means for closing off the normal supply of fluid to the single flow section and for delivering fluid thereto from a stage of lower pressure of the high pressure section under reduced power conditions.

14. A turbine unit comprising a multi-stage high pressure section, a separate double flow low pressure section, a separate single flow low pressure section, means for delivering fluid from one stage of the high pressure section to the single flow section, means for delivering fluid from a stage of lower pressure of the high pressure section to the double flow section, and means for closing off the normal supply of fluid to the single flow section and for delivering fluid thereto from a stage of lower pressure of the high pressure section and for cutting off the supply of fluid to the double flow section, under reduced power conditions.

15. A turbine unit comprising a high pressure section and two low pressure sections, each section including ahead and reversing elements, means for operating the

ahead elements of the low pressure section in parallel on fluid discharged from the ahead element of the high pressure section and means for operating the reversing elements of the low pressure elements in parallel on fluid discharged from the reversing element of the high pressure section.

16. A turbine unit comprising a high pressure section, and two low pressure sections, each receiving fluid from a different stage of the high pressure section, a reversing element in each section and means for delivering fluid discharged from the high pressure reversing element to one or both of the low pressure reversing elements.

17. A turbine unit comprising a high pressure section, two low pressure sections, means for delivering motive fluid from one stage of the high pressure section to one low pressure section, means for delivering steam from another stage of the high pressure element to the other low pressure element, and means for delivering high pressure motive fluid to each low pressure section under emergency conditions.

18. A turbine unit comprising a multistage high pressure section, a multistage low pressure section, means for delivering fluid from a high pressure stage of the high pressure section to a low pressure stage of the low pressure section while developing full power, and means for delivering fluid from a stage of lower pressure of the high pressure section to the initial stage of the low pressure section under reduced power conditions.

19. In a turbine unit a multistage high pressure section, two low pressure sections, at least one of which is provided with a plurality of stages adapted to operate in series, means for delivering fluid from a high pressure stage of the high pressure section to an intermediate stage of the multistage low pressure section and means for delivering fluid from a stage of lower pressure of the high pressure section to the other low pressure section, under full power conditions, and means for delivering fluid from a low pressure stage of the high pressure section to the initial stage of the multistage section and for cutting off the supply of fluid to the other low pressure section while developing reduced power.

20. In a turbine unit a multistage high pressure section, two low pressure sections, at least one of which is provided with a

plurality of stages adapted to operate in series, means for delivering fluid from a high pressure stage of the high pressure section to an intermediate stage of the multistage low pressure section and means for delivering fluid from a stage of lower pressure of the high pressure section to the other low pressure section, under full power conditions, and means for delivering fluid from a low pressure stage of the high pressure section to the initial stage of the multistage section and for cutting off the supply of fluid to the other low pressure section while developing reduced power, a reversing element for each section and means for delivering fluid from the high pressure reversing element to one or both of the low pressure reversing elements.

21. In a turbine unit a multistage high pressure section, two low pressure sections, at least one of which is provided with a plurality of stages adapted to operate in series, means for delivering fluid from a high pressure stage of the high pressure section to an intermediate stage of the multistage low pressure section and means for delivering fluid from a stage of lower pressure of the high pressure section to the other low pressure section, under full power conditions, and means for delivering fluid from a low pressure stage of the high pressure section to the initial stage of the multistage section and for cutting off the supply of fluid to the other low pressure section while developing reduced power, a reversing element for each section, means for delivering fluid from the high pressure reversing element to one or both of the low pressure reversing elements.

22. A turbine unit comprising a high pressure section adapted to pass all fluid required under full power conditions and at least two low pressure sections, characterized by the fact that means are employed for delivering motive fluid from different stages of the high pressure section to the different low pressure sections under full power conditions.

In testimony whereof I have hereunto subscribed my name this 26th day of September, 1916.

HENRY F. SCHMIDT.
